DESIGN FOR A HÆMOMETER CASING

Robert E. Klett, Kent, Conn., assignor to Klett
Manufacturing Co., Inc., New York, N. Y., a
corporation of New York

Application June 13, 1935, Serial No. 57,251

Term of patent 7 years

To all whom it may concern:

Be it known that I, Robert E. Klett, a citizen
of the United States, residing at Kent, in the
county of Litchfield, State of Connecticut, have
invented a new, original, and ornamental Design
for a Hæmometer Casing, of which the following
is a specification, reference being had to the ac-
companying drawing, forming part thereof, in
which:

Fig. 1 is a front elevation of a hæmometer
casing showing my new design;

Fig. 2 is a rear elevation; and

Fig. 3 is a section on the line 3—3 of Fig. 1.
I claim:

The ornamental design for a hæmometer cas-
ing substantially as shown.

ROBERT E. KLETT.
